(57) **CLAIM**

The ornamental design for a horizontal display, as shown and described.

DESCRIPTION

FIG. 1 is a front perspective view of a horizontal display embodying the principles of the present invention, the display being illustrated mounted to a back support shown in phantom lines that does not form a part of the claimed invention, the display further illustrated with a plurality of display shelves, all of which are shown aligned with one another in a central position;

FIG. 2 is a front view of the horizontal display;

FIG. 3 is a side view of the horizontal display as seen from the right-hand side thereof, the opposite side view being a mirror image thereof;

FIG. 4 is a top view of the horizontal display;

FIG. 5 is a top view of the horizontal display similar to FIG. 4, but in which an uppermost display shelf is shown pivoted to the left from that of FIG. 4, a next lower display shelf is shown in the central position, and a next lower display shelf is shown pivoted to the right from that shown in FIG. 4; and, FIG. 6 is a perspective view similar to FIG. 1 showing the display shelves pivoted into staggered positions.
